CLAIM

The ornamental design for an anti-eavesdropping device, substantially as shown and described.

DESCRIPTION

FIG. 1 is a perspective view of an anti-eavesdropping device.

FIG. 2 is a front view of the network device of FIG. 1.

FIG. 3 is a rear view of the network device of FIG. 1.

FIG. 4 is a right side view of the network device of FIG. 1.

FIG. 5 is a left side view of the network device of FIG. 1.

FIG. 6 is a top view of the network device of FIG. 1; and,

FIG. 7 is a bottom view of the network device of FIG. 1.

The broken lines depict portions of the anti-eavesdropping device that form no part of the claimed design. The oblique line shading shown in FIGS. 1 and 6 represents a reflective surface.
